ROLL MOUNTING

Christen R. Kaddeland, Shelton, Conn., assignor
to Harris-Seybold-Potter Company, Cleveland,
Ohio, a corporation of Delaware

Application January 5, 1938, Serial No. 183,462

1 Claim. (Cl. 242—64)

This invention relates to means for mounting rolls of paper or other web material to be fed to a machine for operating upon the material. The invention is disclosed herein as applied to a printing press, in which the web of paper is first cut into sheets and the sheets are then fed into the press where they are printed and delivered onto a pile. Obviously, however, the invention is applicable to other types of machines.

One of the objects of the invention is to provide a compact, accessible, and efficient multiple roll mounting capable of accommodating a roll which is large in diameter in comparison to the size of the mounting.

It is a further object to provide a roll mounting particularly adapted to receive a fresh roll after the roll which is being operated upon has been reduced in size to a considerable extent.

Another object is to provide a construction for a roll mounting that will be durable, convenient, safe, and efficient in operation.

A further object is to provide a roll mounting in which the roll supporting members may be adjusted for different widths of web conveniently and accurately.

A still further object is to provide a construction which will permit the convenient and accurate adjustment of the position of the web laterally in relation to the machine which is to operate upon it.

Fig. 1 is a diagrammatic elevational view of a multi-color printing press to which this invention may be applied.

Fig. 2 is an enlarged view of the multiple roll mounting taken in section through the center of the machine as indicated by the line 2—2 of Fig. 3.

Fig. 3 is an end view of the roll mounting.

Fig. 4 is a plan view taken substantially on the line 4—4 of Fig. 2.

Fig. 5 is a side view corresponding to Fig. 2 but with a fresh roll shown in the act of being inserted while the machine continues to operate upon the previous roll.

Fig. 6 is a diagrammatic perspective view of one end of the roll frame.

Fig. 7 is a detail sectional view of a fragment of the roll frame, taken on the line 7—7 of Fig. 9.

Fig. 8 is a detail sectional view on the line 8—8 of Fig. 7.

Fig. 9 is a fragmental plan view, partly in section on the line 9—9 of Fig. 7, showing a portion of a roll spider and means for adjusting the same.

Fig. 10 is a central sectional view of a retractable spindle which may be employed in connection with the invention, and

Fig. 11 is a detail sectional view of the same, taken substantially on the line 11—11 of Fig. 10.

Referring to Fig. 1, 1 is a foundation or base arranged to support the framework 2 of a web feeding and sheet cut-off mechanism and a multi-color printing press, 3, arranged to print on the cut off sheets and deliver them by means of the endless conveyor 4 to a pile of finished product 5. A roll of paper 6 is supported by a carrier indicated generally as 7, the roll being mounted to turn freely upon spindles mounted in the carrier.

The web 9 is led from the roll 6 over a guide roller 10, around web tensioning rollers 11 and 12, around the web driving rollers 13 and 14 and their associated pressure rollers 15 and 16, thence between the rotary cutting cylinders 17 and 18 where the web is cut into sheets of the desired length. The cut sheets are then carried between adjacent courses of endless tapes 19 and 20, to the feed rollers 21 and 22, which in turn feed the sheets to the impression cylinder 23 of the printing press where they are printed in one or a plurality of colors and delivered onto the finished pile.

The mechanism may be driven in any usual manner. In the example shown, the press drive shaft 24, through bevel gears 25 and 26, drives the vertical shaft 27 which furnishes the motive power for the web feeding and sheet cut-off mechanism during its normal operation. The vertical shaft 27 through bevel gear 28 drives the cutting cylinder 17 which in turn drives intermediate gears 29 and 30, 31, 32 and 33, the last of which drives the rollers 13 and 14 which serve to advance the web of paper to the cutting cylinders. Intermediate gear 31 drives shaft 34 which through an electrically controlled differential gear unit 35 drives the output shaft 36, which through bevel gears actuates the belt driving roll 37.

Mounted on roller 37, idler roller 38 and pulleys 39 are a plurality of leather belts 40 which bear against the surface of the paper roll 6. Through the gearing indicated these belts are driven with a speed corresponding approximately to the desired speed of the web for releasing the web from the roll. The speed of the belts 40 however is variable to cause increase or decrease in the rate the web is released from the roll to thereby maintain uniform tension in the web 9. The actuation and control of the web is shown

only diagrammatically since the present invention is not concerned directly with this mechanism. For a more detailed description of suitable mechanism for actuating the sheet feeding mechanism, cutting cylinders, web driving rollers, and web tensioning mechanism, reference is made to my copending applications Serial No. 183,463, now Patent No. 2,222,462, and Serial No. 183,464, now Patent No. 2,233,922 filed of even date herewith.

It should also be noted for the sake of clearness that the belts 40, which as previously described bear against the surface of the roll 6 for the purpose of maintaining uniform tension in the web 9, are held against the roll with the proper pressure by means of the weights 120, there being a separate weight for each belt. Each weight is formed in a U shape and is provided with an axle 121 which supports the pulley 39. A bracket 122 which is clamped to a cross bar 123 in any desired position is provided with a slide bar 124 which engages a groove 125 in each side of the weight thus allowing the weight to act under gravity to lower the pulley 39 as far as permitted by the length of the belt 40.

Referring now more specifically to Figs. 2 and 3, the frame members 2 which are joined by spacer members 41 are formed with bosses 42, 43 which support trunnions 44 and 45 in line with each other on opposite sides of the machine. Keyed to the inner end of trunnion 44 and rotatable therewith is an elongated support member 46 formed with capped ends 47, which together constitute one end member of a revoluble frame. On the other side of the machine and keyed to trunnion 45 is a similar elongated member 48 constituting the other end member of the frame. The caps 47 of the members 46 and 48 are arranged to hold in fixed relation cross rods 49 and 50 which constitute the remaining members of the revoluble frame above referred to, which is rigid, rectangular in form, and is carried in the main frame 2 upon the trunnions 44 and 45. An important characteristic of such a frame is the absence of a central connecting member between the end members of the frame. Because of this characteristic the frame will be referred to hereinafter as a hollow frame.

Each of the cross rods 49 and 50 is provided with a series of rack teeth cut in its side for a purpose to be explained later. Upon the cross rods 49 and 50 are adjustably mounted two diamond shaped roll supporting spiders 51 and 52. Spider 52 carries at two of its points a pair of rotatable spindles 53 and 54, while spider 51 similarly carries another pair of spindles 55 and 56, whose construction and operation will be described later in connection with Fig. 10.

Upon the pair of spindles 53, 55 or 54, 56 as the case may be, the roll of paper 6 is mounted, the spindles being inserted into the ends of the hollow core provided as a center about which the web of paper is rolled. It will be noted, as particularly shown in Fig. 2, that the construction just described permits the insertion of a paper roll whose radius is greater than the radial distance from the center of rotation of the carrier frame to the center of rotation of the paper roll. Thus while paper is still being fed from a roll whose size has been reduced a necessary amount a new full size roll may be placed in the other part of the carriage in position ready for being turned into operative position as soon as the previous roll has been entirely exhausted. The size of carriage required for a roll of given

diameter is, therefore, materially reduced and the whole mechanism made more compact with a resulting saving in floor space and height.

The construction and manner of operation of the retractable spindles 55 and 56 are shown in Figs. 10 and 11. The portion of the spindle which is inserted in the end of the hollow core of the paper roll comprises a hollow member 57 with a tapered outer wall and a collar 58, which are arranged to be clamped to the outer race of a combination radial and thrust anti-friction bearing 59, the inner race of which is mounted on the reduced end of a non-rotatable stud 60 which is held in the collar 61 by means of the set screw 62. The collar 61 is slidably keyed in the frame member 51 so that the spindle may be retracted from or inserted in the paper roll core. The collar 61 also has inserted in it the nut 63 held in place by set screw 64 and having a threaded hole which a screw 65 engages. The screw 65 has a shouldered portion 66 which engages the inner portion of a cover plate 67 which is bolted to the spider 51 around the cylindrical opening in which the collar 61 is mounted. To the outer end of screw 65 is keyed a hand wheel 68, the hub of which engages the outer face of the cover plate 67. Thus when the wheel 68 is turned the screw 65 turns but may not move lengthwise. The threads in the nut 63 however cause the collar 61 and the spindle member 57 to move in and out in relation to the spider 51.

A ratchet 69 which is fixed to the hand wheel 68 is engaged by a pawl 70 which is urged into contact with ratchet 69 by the spring 71, both the pawl and spring being mounted on a pawl carrier 72 which is keyed to the outer portion of the cover plate 67.

It will be seen that these parts may be designed so that turning the hand wheel 68 in the clockwise direction will cause the spindle 57 to move to the right in Fig. 10 and that the pawl 70 will ride freely over the teeth of the ratchet 69. By manually raising the pawl 70 against the spring 71 to disengage the pawl from the ratchet the hand wheel may be moved in a counterclockwise direction and the spindle 57 moved to the left in Fig. 10. It will be seen that the construction just described is convenient in operation and avoids any possibility of the spindle accidentally being retracted while supporting a paper roll.

In order that the frame or carriage may accommodate rolls of different widths the spiders 51 and 52 are movably mounted on the cross rods 49 and 50 as previously mentioned. These spiders are maintained in true parallelism in different positions and may be moved readily from one position to another. To this end they are provided with means on cross rods 49 and 50 cooperating with the rack teeth 73 so that both ends of each of the spiders 51 and 52 will be moved simultaneously. This means in each instance consists of a shaft 74 the opposite ends of which are squared, as indicated at 75, for receiving a wrench. Inwardly of the squared portions gear teeth 76 are cut in the shaft. In order that the shaft 74 may not slide out of position it is provided with a slot 77 which is engaged by the end of a set screw 78 (Fig. 8) carried by the web 79 of the spider 51 or 52 as the case may be. The shaft 74 is mounted at its two ends in the spider. Upon rotation of the shaft the engagement of gear teeth 76 with the rack teeth 73 in the stationary cross rods 49 and 50 will cause the spider to move along these

cross rods smoothly and in parallelism with itself. At any desired position of spiders 51 and 52 the screws 80 which hold the caps 80' of the spiders in place may be tightened so that the cross shafts 49 and 50 are firmly clamped.

Referring again to Fig. 3, the trunnions 44 and 45 are provided with endwise clearance so that the entire framework consisting of these trunnions, supports 46 and 48, and cross rods 49 and 50 as well as the mechanism carried by these cross rods may be accurately adjusted crosswise of the machine for the purpose of placing the web of material in an accurate position with respect to the machine operating upon it. For this purpose the trunnion 44 is provided with a recess 90 for the purpose of receiving an anti-friction bearing 91 mounted on the end of a screw 92, the outer race of this bearing being held in fixed relation to the trunnion 44 by means of a retaining plate 93. The threads on this screw 92 engage threads in a plate 94 which is bolted to a combination gear cover and bracket 95 which in turn is bolted to the main frame 2 by the screws 96. Keyed to the outer end of the screw 92 is hand wheel 97 and between the hand wheel and the plate 94 and on the screw 92 is a lock nut 98 which is provided with a handle for convenience. It will be seen that when the lock nut 98 is loosened and the hand wheel 97 is turned the screw 92 travels in or out of the plate 94 and carries with it the trunnion 44, thus moving the entire paper roll frame laterally of the machine.

For the purpose of placing a fresh roll in operative position when a previous roll has been partly or fully exhausted, mechanism is provided for revolving the entire paper roll frame into the desired position and holding it there without further forward or backward movement. Keyed to the outer end of each of the trunnions 44 and 45 are gears 101 which engage pinions 102. Each of these pinions is mounted on one of a pair of duplicate shafts 103 (see Fig. 4) which carry worm wheels 104 that engage worms 105 on duplicate shafts 106 which are joined by couplings 107 to duplicate shafts 108 on opposite sides of the machine. The shafts 108 are equipped with bevel gears 109 which mesh with other bevel gears 110 which are mounted at the two ends of a cross shaft 111. Keyed to the cross shaft 111 is a pulley 112 which is driven through a belt 113 by a motor 114 which may be started and stopped by a manually operated switch.

By means of the mechanism just described it will be seen that a new paper roll may be brought into operative position without any tendency to

5 twist the roll frame as would be the case if this frame were revolved from one end only. It is also to be noted that the worms 105 in conjunction with the worm wheels 104 act as locks to hold the paper roll in any desired position.

10 The operation of the mechanism for the insertion of a fresh roll of paper is as follows: When the roll 6 upon which the machine is operating has become exhausted sufficiently to permit the insertion of a new full sized roll the entire roll frame 7, which during operation of the machine may occupy the position shown in Fig. 2, is rotated by motor 114 about its supporting trunnions 44 and 45 into the full line position of Fig. 5 or any other convenient position for the insertion of a fresh roll.

15 The fresh roll 136 which is carried on a truck 131 is brought into position between the spindles 54, 56. Spindle 56 has previously been retracted sufficiently to permit the roll to pass between the spindles. The truck may then be moved slightly toward the right, as the machine is viewed in Fig. 3, to carry the hollow core of the roll into close engagement with spindle 54, after which spindle 56 is again moved inwardly by hand wheel 68 until the latter spindle also closely engages the core.

20 The roll frame 7 is then revolved sufficiently to raise the roll 130 off the truck 131 so that the latter may be removed. The dotted lines in Fig. 5 show the frame rotated slightly for this purpose. After the removal of the truck 131 the frame may be restored to any desired operating position for the completion of the operation of the machine upon roll 6.

25 As is evident from the construction all the operations involved in placing a fresh roll of paper between the spindles 54, 56 may be accomplished while the machine is in operation and the web of paper is being withdrawn from the roll 6.

30 Having thus described my invention, I claim:
A roll carrier adapted to be revolvably mounted in a supporting structure, comprising end members, aligned trunnions fixed to said end members having bearing in said supporting structure, 45 a pair of spaced longitudinal members connecting said end members on opposite sides of said trunnions to form a rigid, hollow frame revolvble about said trunnions as a center, and roll supporting means for two rolls carried by said frame comprising two pairs of spindles, said longitudinal members being spaced apart a distance at least as great as the spacing of said pairs of spindles.

35 55 CHRISTEN R. KADDELAND.
